INVENTOR:

Daniel William MacMillan

by Chas. H. Luther
ATTORNEY-

UNITED STATES PATENT OFFICE.

DANIEL WILLIAM MACMILLAN, OF PROVIDENCE, RHODE ISLAND.

SOFT-COLLAR FASTENER.

1,368,275.

Specification of Letters Patent. Patented Feb. 15, 1921.

Application filed December 6, 1920. Serial No. 428,738.

To all whom it may concern:

Be it known that I, DANIEL WILLIAM MACMILLAN, a citizen of the United States, residing at Providence, in the county of Providence and State of Rhode Island, have invented a new and useful Improvement in Soft-Collar Fasteners, of which the following is a specification.

My invention has reference to an improvement in soft collar fasteners and more particularly to an improvement in my soft collar fastener shown in my United States Patent No. 1,359,612, issued to me November 23, 1920.

The object of my invention is to improve the construction of such a soft collar fastener or holder, whereby the holding power of the fastener on the collar is increased without injury to the collar, the construction simplified and the cost of construction materially reduced.

My invention consists in the peculiar and novel construction of a soft collar fastener having details of construction, as will be more fully set forth hereinafter and claimed.

Figure 1 is an edge view of my improved soft collar fastener in the normally closed position.

Fig. 2 is a back view of the fastener with one end of the spring back bar broken away.

Fig. 3 is a longitudinal sectional view taken on line 3, 3 of Fig. 2.

Fig. 4 is a transverse sectional view taken on line 4, 4 of Fig. 1.

Fig. 5 is a detail longitudinal sectional view taken on line 5, 5 of Fig. 2, and

Fig. 6 is a plan view of the blank from which the rigid front bar is formed.

Figs. 1, 2, 3 and 6 are enlarged and Figs. 4 and 5 are still further enlarged.

In the drawing 7 indicates a rigid curved front bar, and 8 a spring back bar. The rigid front bar 7 is formed from a blank as shown in Fig. 6, to have a curved front 9,

longitudinal edge ribs 10, 10 on the back, folded over side flaps 11, 11, on the back at each end, semi-circular ends 12, 12 and cen-

tral spring back bar holding members 13, 13 at each side and which are forced over from each side and down onto the back bar, to hold the back bar in place. Each side flap 11, has a slightly concaved under

portion 14 and rounded inner and outer edges 15, 15, and each of the semi-circular

ends 12, 12 has a rounded edge 16, as shown in Fig. 5. As the side flaps 11, 11 are brought over into place simultaneously with forming the longitudinal side ribs 10, 10, the additional operations of bending the ends of the front bar over to form the flaps, as in my previous patent, are eliminated. The side ribs 10, 10 and the flaps 11, 11 form a pocket 17 in the back of the front bar at each end of the front bar, each pocket having three point contact edges 18 and 19, 19, as shown in Figs. 2, 3, 4 and 5. The spring back bar 8 is shaped to have a flat central portion 20 and at each side of this central portion an outwardly curved spring portion 21 merging into a curved spring portion 22, which is curved parallel with the curved front bar 7. The curved portion 22 ends in a rounded end 23 and from this rounded end 23 the bar extends back at an angle, forming an angular spring clamping member 24 which terminates into a rounded clamping end 25 which normally enters the pocket 17, as shown in Figs. 3 and 5. The width of the spring back bar 8 is slightly less than the width of the pockets 17, 17, as shown in Fig. 4 thereby allowing the soft collar to more easily enter the pockets and more firmly securing the fastener to the collar.

By this construction the heretofore operations of bending over the ends of the front bar, to form the ends of the pockets 17, 17 are eliminated, thereby reducing the cost of construction, the inner rounded edges 15, 15 on the flaps 11, 11 prevents injury to the collar and the shape of the spring back bar gives more room for the ends of the collar, thereby allowing for different shapes and sizes of collars.

Having thus described my invention I claim as new:

1. A soft collar fastener comprising a rigid front bar having longitudinal edge ribs on the back and bent over side flaps forming end pockets in the back of the front bar, a spring back bar having portions parallel with the front bar and rounded ends which normally enter the pockets in the front bar, for the purpose as described, and means for securing the spring back bar to the front bar.

2. A soft collar fastener comprising a rigid front bar having semi-circular ends, longitudinal edge ribs on the back, bent over side flaps on the edge ribs and forming end pock-

ets in the back of the front bar, a spring back bar having spring portions parallel with the front bar and bent back angular spring portions having rounded ends which normally enter the pockets in the front bar, for the purpose as described, and means for securing the spring back bar to the front bar.

3. A soft collar fastener comprising a curved rigid front bar having semi-circular ends with rounded edges, longitudinal edge ribs on the back, bent over side flaps forming end pockets in the back of the front bar, said side flaps having slightly concaved under-sides and rounded edges, a spring back

bar having a flat central portion and at 15 each side of the central portion an outwardly curved portion merging into a curved portion parallel with the front bar, said curved parallel portion merging into a rounded end which merges into an angular 20 bent back portion that terminates into a rounded end, normally entering the pocket in the back bar, for the purpose as described, and means for securing the flat central portion of the spring back bar to the front bar. 25

In testimony whereof I have signed my name to this specification.

DANIEL WILLIAM MACMILLAN.
